[57] CLAIM

The ornamental design for a seat, as described and shown.

DESCRIPTION

FIG. 1 is a front perspective view of a seat showing my design in the form of a sofa;

FIG. 2 is a side elevational view of the seat;

FIG. 3 is a front perspective view of the seat in the form of a loveseat; and

FIG. 4 is a front perspective view of the seat in the form of an armchair.

The sides of the seat not shown are mirror images of the side shown in FIG. 2, while the undisclosed rear surfaces are conventional in appearance.

FIG. 1

FIG. 2

FIG. 3

FIG. 4
